US00D692134S

(12) **United States Design Patent**
Lee-Sepsick

(10) **Patent No.:** US D692,134 S
(45) **Date of Patent:** ** Oct. 22, 2013

(54) **DEVICE FOR SAMPLING TISSUE**

(75) Inventor: **Kathy Lee-Sepsick**, Suwanee, GA (US)

(73) Assignee: **Femasy Inc.**, Suwanee, GA (US)

(**) Term: **14 Years**

(21) Appl. No.: **29/418,924**

(22) Filed: **Apr. 23, 2012**

(51) LOC (9) Cl. **24-02**

(52) U.S. Cl.

USPC **D24/146**

(57) **CLAIM**

The ornamental design for a device for sampling tissue, as shown and described.

DESCRIPTION

FIG. 1 is a perspective view of a device for sampling tissue showing my new design;

FIG. 2 is a front elevational view of the device of FIG. 1;
FIG. 3 is a back elevational view of the device of FIG. 1;
FIG. 4 is a left side elevational view of the device of FIG. 1;
FIG. 5 is a left side elevational view of the device of FIG. 1 with the sheath opened;

FIG. 6 is a right side elevational view of the device of FIG. 1;
FIG. 7 is a top elevational view of the device of FIG. 1;
FIG. 8 is a bottom elevational view of the device of FIG. 1; and,

FIG. 9 is a perspective view of the device of FIG. 1.
The break applied to the claim in FIGS. 4–8 has been applied for ease of illustration and forms no part of the claim.

1 Claim, 5 Drawing Sheets

FIG. 2

FIG. 3

FIG. 9
